US0D1008208S

(12) **United States Design Patent** (10) **Patent No.:** **US D1,008,208 S**
(45) **Date of Patent:** **** Dec. 19, 2023**

(54) **RECORD PLAYER**

(71) Applicant: **Guangzhou Changyi Electronic Technology Co., Ltd.**, Guangzhou (CN)

(72) Inventor: **Bingzhao Qiu**, Guangzhou (CN)

(73) Assignee: **Guangzhou Changyi Electronic Technology Co., Ltd.**, Guangzhou (CN)

(**) Term: **15 Years**

(21) Appl. No.: **29/888,413**

(22) Filed: **Mar. 30, 2023**

(51) **LOC (14) Cl.** **14-01**

(52) **U.S. Cl.**

USPC **D14/202**

(57) **CLAIM**

The ornamental design for a record player, as shown and described.

DESCRIPTION

FIG. 1 is a front, right and top perspective view of a record player, showing my design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the record player in an open state.

The broken lines depict portions of the record player that form no part of the claimed design.

1 Claim, 9 Drawing Sheets
